UNITED STATES PATENT OFFICE.

JESSIE M. HIGLEY, OF NILES, CALIFORNIA.

VALANCE-SUPPORT.

SPECIFICATION forming part of Letters Patent No. 674,609, dated May 21, 1901.

Application filed December 21, 1900. Serial No. 40,656. (No model.)

To all whom it may concern:

Be it known that I, JESSIE M. HIGLEY, a citizen of the United States of America, residing at Niles, county of Alameda, and State 5 of California, have invented certain new and useful Improvements in Valance-Supports; and I hereby declare the following to be a full, clear, and exact description of the same, reference being had to the accompanying 10 drawings, forming a part of this specification.

My invention relates to certain improved devices for supporting valances around bedsteads and providing convenient means of applying and removing the same.

15 My improvements consist of extensible and removable cords or rods on which the valances are rove, adapted to be fastened to the posts of a bedstead at its corners, preferably by means of detachable and adjustable 20 collars provided with eyes or sockets to which the supports are attached by hooks, as illustrated in the drawings herewith, forming a part of this specification.

The object of my invention is to provide 25 means whereby valances can be instantly attached to and removed from bedsteads for the purpose of sweeping beneath the same or for any other purpose.

Referring to the accompanying drawings, 30 Figure I is an elevation in perspective of a metallic bedstead provided with my improvements. Fig. II is a top view of a clamping-collar to which the valance-supports are attached. Fig. III is a similar view of an open 35 or spring collar, also provided with fastenings or eyes to receive the valance-supports. Fig. IV is a broken side elevation of an elastic supporting-cord provided with hooks to engage the-ends. Fig. V is a similar view of 40 an extensible rod or tube such as can be employed instead of an elastic cord for short lengths. Fig. VI is a section showing the manner of inserting screw-eyelets in the collar shown in Fig. II.

45 The attachment of valances, especially to metallic bedsteads, in a manner to permit their being instantly applied or removed is a matter of much convenience, especially in sweeping and cleaning, and to this end I pro-

vide devices as now to be described, referring 50 to the drawings.

The bedstead A in Fig. I is of the common construction, furnished with valances B, made of any suitable fabric and rove on a through-support C, made, preferably, of elastic cord 55 when of much length.

For attachment to the bedposts D, I employ, preferably, elastic and adjustable embracing collars E, that when adapted for bedposts of various sizes are made to overlap, as in Fig. 60 II, and are held by a screw F, or when made to fit a particular size of bedposts can be sprung around the posts D, as shown in Fig. III. In these collars are inserted eyes or 65 lugs G to receive the hooks H on the elastic cords C, or a single elongated eye J can be employed to receive two hooks, as in Fig. III, two being preferable in the case of open or spring collars, because tending to close and clamp them around the bedpost D. 70

When the length is not great, as at the head and foot of bedsteads, especially when these are of less than full width and when the elastic cords do not stretch enough to be applied and removed conveniently, and also in some 75 cases for ornament, I employ extensible polished rods, as shown in Fig. V, the ends L sliding outward and inward in the tubular center part M in the usual manner of curtain-rods. In the case of extensible metallic rods, 80 as shown in Fig. V, these being inflexible, the hooks N are made angular, as shown, the weight of the rods serving to prevent accidental disengagement.

When the overlapping collars (shown in 85 Fig. II) are employed, these can be expanded and contracted to fit around bedposts D of various sizes, the screw F being shifted accordingly, a number of screwed eyelets C being inserted for that purpose at spaced distances, as shown in Fig. VI.

It will be obvious that the particular construction of these devices, especially the collars E, admits of modification as to material, ornament, and mode of manufacture, or the 95 eyes G may be attached to the bedposts in any suitable manner. The methods shown in Figs. II and III of the drawings are found

satisfactory in practice. The collar shown in Fig. II I make, preferably, of brass and those shown in Fig. III of steel, either of which can be left plain or electroplated with silver, 5 nickel, or other metals.

Having thus explained the nature and objects of my invention and the manner of applying the same, what I claim as new, and desire to secure by Letters Patent, is—

10 In valance-supports, the extensible support on which the valance is rove, having hooks at its extremities, in combination with

detachable collars E, for attachment to the uprights of a bedstead, said collars provided with eyes for receiving the said hooks, substantially as specified.

In testimony whereof I have signed my name to this specification in the presence of two subscribing witnesses.

JESSIE M. HIGLEY.
